UNITED STATES PATENT OFFICE.

MANDLEY J. AUSTIN, OF BUFFALO, NEW YORK, ASSIGNOR OF ONE-HALF TO GEORGE E. BOORMAN, OF BUFFALO, NEW YORK.

LOCK-VALVE.

985,100.

Specification of Letters Patent. Patented Feb. 21, 1911.

Application filed August 29, 1910. Serial No. 579,500.

To all whom it may concern:

Be it known that I, MANDLEY J. AUSTIN, a citizen of the United States, and resident of Buffalo, in the county of Erie and State 5 of New York, have invented new and useful Improvements in Lock-Valves, of which the following is a specification.

My invention relates to improvements in lock valves, and it has for its primary object the provision of a valve of this type which is particularly designed for use in 10 automobiles for shutting off the flow or feed of gasoline to the carburetor, it being adapted to be placed between the gasoline 15 feed chamber and the carburetor, and when closed, to be locked so that persons intending to use the automobile without authority, or stealing the same will be prevented from running it for any distance, as the very 20 small quantity of gasoline which may be in the carburetor will be consumed after running about 100 feet.

Another object of my invention is the production of a lock valve of this type which 25 is so constructed that a portion of the locking mechanism thereof will be within convenient reach of the operator; also the provision of a valve that can be used in other places where it is desirable to control the 30 supply or feed of fluids or gases.

A still further object is the production of a valve of this kind which is simple in construction, easy to manipulate and which can be manipulated only by the person in 35 possession of the key specially designed for the particular valve in use.

To these ends the invention consists in the construction, arrangement, and combination of parts to be hereinafter described and particularly pointed out in the subjoined claims.

In the drawings,—Figure 1 is a central vertical section through the complete valve showing the same in locked position. Fig. 2 is a similar section showing the valve in 45 unlocked or open position. Fig. 3 is a plan view of the valve and a portion of the floor, seat, or other part of an automobile to which the upper end of the valve is secured. Fig. 4 is a horizontal section taken through the 50 casing above the coil spring. Fig. 5 is a detached perspective view of the detent spring by means of which the valve is locked in closed position.

Referring now to the drawings in detail, like letters of reference refer to like parts 55 in the several figures.

A represents the valve-body proper having a passage *a* for the gasoline or other liquid or for the gas, as the case may be, the opposite ends of said valve-body being internally threaded, as at *a*¹, for application thereto of supply or feed pipes. At the upper end of the valve-body is a stuffing box B which is externally threaded, as at *b*, and in the said valve-body is arranged for vertical sliding movement the valve proper C, it having a valve stem *c* extending through the stuffing box B, to the upper end of which a short sleeve D is threaded or otherwise attached as shown at *d* Figs. 1 and 2. This 70 sleeve is closed at its upper end and has a key-hole E formed in said end through which a key *e* of suitable formation is adapted to be inserted. Surrounding said sleeve D with its upper end and threaded onto the externally threaded portion of the stuffing-box B with its lower end, is a suitable casing F which may be of any desired formation and of the required length to extend to within convenient reach of the operator, 80 said casing having preferably an outstanding flange *f* at its upper end and extending through the floor G or some other part of the automobile, the casing being secured at its upper end by means of screws *f*¹. 85

When in normal or unlocked position, the short sleeve D extends out through the upper end of the casing F, as shown in Fig. 2; but when the valve is closed and locked, the upper end of the sleeve is preferably flush 90 with the flange *f* of the casing, as shown in Fig. 1, said sleeve being held in locked position by a detent spring H fastened at its lower end to the casing F and extending up into the sleeve D to a point within convenient reach of the key *e*, said detent spring having its upper end off-set, as at *h*, to provide a portion adapted to co-act with said key and at a point between said off-set portion and its lower end, a lock lip *h*¹ is formed 95 having a beveled face *h*² for a purpose to be presently described. Said lock lip is adapted to enter an opening I formed in the sleeve D and thus lock said sleeve, the valve stem *c* and the valve C in closed position. 100 105

In order that the key hole E in the sleeve

D be retained in alinement with the detent spring H, I groove the casing F internally, as at J, and provide the sleeve D with a projection K which fits into said groove, said 5 groove being disposed vertically so that the sleeve D may rise and lower within the casing.

In order that the sleeve D may be removed from the valve stem c, the projection 10 is preferably in the form of a screw threaded into said sleeve so that the projection may be removed from the sleeve through an opening L formed in the casing. Surrounding the valve stem c is a coil spring M bearing 15 with its lower end against the top of the stuffing box B and with its upper end against a collar N on said stem which collar is held in fixed position by a pin n passing through said valve stem, said spring serving to raise 20 the valve C and project the short sleeve D from its casing after the key e has disengaged the lock lip h¹ of the detent spring from the opening I in said sleeve.

The normal position of the parts is shown 25 in Fig. 1 of the drawings, the valve being open to permit the feeding of gasolene to the carbureter. When it is desired to shut off the flow of the gasolene, it is simply necessary to depress the sleeve D which, 30 through its connection with the valve C causes the latter to be moved into closed position shown in Fig. 1, and as soon as the lower end of the sleeve D engages the lock lip h¹ of the detent spring H, said spring is 35 deflected inward and remains in such position until the opening I in said sleeve is brought in line with said lock-lip whereupon said lip immediately enters said opening due to the fact that the detent spring is permitted 40 to return to normal position.

When the valve is closed, as shown in Fig. 1, the spring M is compressed so that upon insertion of the key e into the key-hole E at the top of the sleeve D, and the turning of 45 the same, it engages the off-set portion of the detent spring, deflects the same to move the lock lip h¹ thereof out of the opening I in said sleeve, whereupon the spring immediately expands and opens the valve and elevates the sleeve D.

Having thus described my invention, what I claim is,—

1. A lock valve comprising a valve casing having a passage, a slide valve to open and close said passage, a valve stem on said slide valve extending through said valve casing, a sleeve at the upper end of said valve stem movable therewith, means to lock said sleeve at the end of its movements in one direction,

and means to open said valve and move said sleeve in the other direction.

2. A lock valve comprising a valve casing having a passage, a slide valve to open and close said passage, a valve stem for said slide valve extending through said valve casing, a casing extending upward from said valve casing through which said valve stem extends, a collar on said valve stem, a spring surrounding said valve stem between said collar and said valve casing, a sleeve 65 slideable in the casing secured to said valve casing and itself attached to said valve stem, and means to lock said sleeve in depressed position within said second-mentioned casing.

3. A lock valve comprising a valve casing 70 having a stuffing box and a passage, a slide valve in said casing to open and close said passage, a valve stem secured to said valve and extending through said stuffing box, a cylindrical casing secured to said valve casing and surrounding said valve stem, a sleeve surrounding the upper end of said valve stem having its upper end closed and being slideable within said cylindrical casing, said sleeve having a key hole at its upper end, 75 locking means engaging said sleeve to hold the same in its innermost position, said locking means being adapted to be engaged by a key inserted through said key-hole, and a spring for causing said slide valve to be 80 opened and said sleeve to be projected when said locking means is actuated.

4. A lock-valve comprising a valve having 85 a slide valve therein and a valve stem projecting therefrom, a cylindrical casing surrounding said valve stem and having a longitudinal internal groove, a sleeve at the outer end of said valve stem having a projection entering said groove, an opening between its ends and a key-hole at its upper 90 end, a detent spring fastened to said cylindrical casing and provided with a lock lip adapted to enter the opening in said sleeve, said detent spring being adapted to be actuated by a key inserted through said key-hole, 95 a spring surrounding said valve stem and acting to move the same outward when said detent spring is actuated, said spring moving outward with the valve stem and said slide valve being drawn into open position during the outward movement thereof.

In testimony whereof, I have affixed my signature in the presence of two subscribing witnesses.
